UNITED STATES PATENT OFFICE.

GEORGE A. WILLARD, OF PETERBOROUGH, NEW HAMPSHIRE, ASSIGNOR TO
THE CHASE LASTING MACHINE COMPANY, OF BOSTON, MASSACHUSETTS.

NIPPER-JAW FOR LASTING-MACHINES.

SPECIFICATION forming part of Letters Patent No. 566,881, dated September 1, 1896.

Application filed February 21, 1896. Serial No. 580,151. (No model.)

To all whom it may concern:

Be it known that I, GEORGE A. WILLARD, of Peterborough, in the county of Hillsborough and State of New Hampshire, have invented an Improved Nipper-Jaw for Lasting-Machines, of which the following is a specification, reference being had to the accompanying drawings, in which—

Figure 1 is a side elevation. Fig. 2 is a central longitudinal section. Fig. 3 is a plan view of my nipper-jaw, and Fig. 4 is a sectional elevation of a modification.

My invention is a nipper-jaw for lasting-machines in which the spring-pressure, by means of which the adjustability of the nippers to different thicknesses of stock is obtained, is provided by compressing a spring and not by stretching a spring, as is the case in nippers heretofore known, as, for example, in patent to Dalpe, No. 536,780, dated April 2, 1895, the result being a nipper much more efficient and durable than any other nipper.

In the drawings, A is the fixed member of the nipper-jaw, having the guides a and projections a' fast to it, one end of the fixed member forming one of the jaws b of the nipper, which acts, in conjunction with the other jaw b , upon the moving member B. The moving member B slides in the guides and is connected to the lever E by links D. The lever E is slotted at its lower extremity and carries a spiral spring F about its lower part, which spring presses at its upper end against the pin d , which connects links D to lever E, and at its lower end against the projections a' . The slotted end of lever E works upon pin a^2 between the projections a' .

The operation is as follows: When the nipper is ready to take hold of the stock, (see Fig. 1,) the spring F tends to force the lever E away from the projections a' until the end of the slot comes in contact with the pin a^2 . When the nipper is closed upon the stock, (see Fig. 2,) the moving member B being prevented by the stock between the jaws b from being drawn inward its full length, the lever is compelled to yield against the resistance of spring F, the yield of lever E being rendered possible by the slot in the lower end of lever E.

In the modification shown in Fig. 4 the lower end of the lever E works upon the pin a^2 , the middle portion of lever E is slotted, and pin d , to which the ends of links D are secured, works in the slot. Spring F surrounds the lower portion of lever E between pin d and projections a' . It will be obvious that by inserting stock between the jaws b the links D, which are fast to moving member B, are in effect shortened and the pin d moved in the slot against the resistance of spring F.

What I claim is—

In combination, jaw members A and B; slotted lever E carrying a spring F and fulcrumed upon member A; spring F and links D connecting lever E and member B; all organized and operating substantially as described.

GEORGE A. WILLARD.
